UNITED STATES PATENT OFFICE.

CHARLES L. JOHANNESOHN, OF DINSMORE, SASKATCHEWAN, CANADA, ASSIGNOR TO
JOHANN MOTORS LIMITED, OF DINSMORE, SASKATCHEWAN.

MECHANICAL MOVEMENT.

Application filed February 13, 1923. Serial No. 618,830.

To all whom it may concern:

Be it known that I, CHARLES L. JOHANNESOHN, a citizen of the Dominion of Canada, residing at Dinsmore, in the Province 5 of Saskatchewan, Dominion of Canada, have invented certain new and useful Improvements in Mechanical Movements; and I do hereby declare the following to be a full, clear, and exact description of the invention, such as will enable others skilled in the 10 art to which it appertains to make and use the same.

This invention relates to new and useful improvements in mechanical movements.

15 One object of the invention is to provide constantly rotatable elements one of which is arranged to pause and then proceed in the same direction.

Another object is to provide a device of 20 this character which includes a plurality of rotatable elements one of which is arranged to pause or stop in its movement while another element approaches it, and then to proceed in the same direction.

25 Another object is to provide a device of this character wherein a rotatable element is arranged to stop in its movement, move in a retrograde direction for a short distance while another element approaches it, and then to proceed in the original direction.

30 Other objects and advantages will be apparent from the following description when taken in connection with the accompanying drawings.

35 In the drawings:

Figure 1 is a side elevation of the mechanism with the side of the casing removed.

Figure 2 is a horizontal longitudinal central sectional view on the line 2—2 of Figure 1.

40 Figure 3 is a vertical transverse sectional view on the line 3—3 of Figure 1.

Figure 4 is a vertical transverse sectional view on the line 4—4 of Figure 1.

45 Figure 5 is an end view of the movable members, showing one position thereof.

Figure 6 is an end view of the members showing another position thereof.

50 Referring particularly to the accompanying drawings 10 represents a casing or housing having the bearings 11 and 12 formed in opposite sides thereof. Secured to the wall of the casing, and surrounding the bearing 12, is a stationary ring gear 13. Disposed 55 transversely through the casing, and having

one end rotatably supported in the bearing 12, is a shaft 14. Keyed on the shaft 14, inwardly of the bearing 12, is a disk 15, and rotatably carried by the disk, at diametrically opposite points, are the stub shafts 16, 60 of the gears 17, said gears being in constant mesh with the ring gear 13, and arranged to travel around thereon. Loosely rotatable on the inner end of the bearing 11 is a disk 18, similar to the disk 15, said disk having the 65 stub shafts 19 at diametrically opposite points, as clearly seen in the drawing. Connected to and extending between the disks 15 and 18, so that said disks will rotate in unison, are the bars or rods 20. Carried by 70 each of the stub shafts 16 and 19, inwardly of the disks, are the radial crank arms 21, and 22, respectively. Rotatably disposed on the shaft 14 is a hollow shaft 23, the inner 75 end of which is disposed against the inner face of the disk 15, and carried by this inner end of the shaft 23, and keyed thereon, is a rockable member 24 having the diametrically opposite arms 25 and 26. It will be noted that the crank arms 21 extend in a direction diametrically opposite to the crank arms 22, and are connected for unitary movement by the arms 27.

80 Loosely rotatable on the shaft 23 is a second hollow shaft 28, and keyed on this shaft 85 is a member 29, similar in construction to the member 24, and having the oppositely extending arms 30 and 31. Pivotedly connected to the outer ends of the crank arms 21, and to the opposite ends of the rockable 90 member 24, are the links 32, while similar links 33 are pivotally connected to the opposite ends of the member 29 and to the crank arms 22.

The shaft 14, as well as the shafts 23 and 95 28, extends outwardly beyond the bearing 11, and formed on the outer end of the shaft 28 are the diametrically opposite radial blades 34 and 35. On the outer end of the shaft 23 there are formed the similar radial blades 36 and 37, the portion of the shaft which carries the blades being slightly enlarged so that its diameter is equal to the diameter of the adjacent and abutting portion of the shaft 28. It will be noted that 100 the blades 34 and 35 extend beyond the end of the shaft 28, so that they overlap the abutting portion of the shaft 23, while the blades 36 and 37 project inwardly beyond the enlarged portion of the shaft 23, and 110

overlap the shaft 28, to a degree equal to the overlapping of the blades 34 and 35, and intermediate the said blades. The shaft 14 projects a slight distance beyond the hollow shaft 23, and serves as a support therefor.

When power is applied to the shaft 14, to rotate the same, the disks 15 and 18 will be carried around, resulting in the rotation of 10 the gears 17, by meshing engagement with the ring gear 13. Thus the gears 17 will have an orbital movement around the gear 13. As the disks 15 and 18 rotate the crank shafts 16 and 19 will be turned, causing the 15 reciprocation of the links 32 and 33, and the rocking movement of the members 24 and 29. It will be understood that the cranks 21 and 22 make complete revolutions, while the rocking members 24 and 29 simply rock 20 on the axis 14, as their ends are reciprocated by the links. It will also be understood that at certain points in the revolution of the cranks 21 and 22, a dead center is reached, but by reason of the fact that the gears 17 25 are in constant mesh with the gear 13, the cranks will be carried past the dead center points. However, when the cranks reach the dead center points, or rather are in close proximity thereto, both when approaching 30 and leaving such points, there will be a pausing or stopping of the cranks, together with the associated blades of the shafts 23 and 28, with the result that when these 35 blades pause or stop, the blades which follow will move up to within a certain distance therefrom, at which time, the first blades will have been moved, by the cranks having passed the dead center points, and will proceed on their course in the original 40 direction. As the following blades approach, reach, and pass the dead centers, they will pause, stop, and then proceed again, the first blades having reached the condition where they become the following 45 blades, and approach these second blades.

There is thus shown a novel and improved device whereby a plurality of constantly rotating members are successively brought to a standstill until another approaches it, when 50 it will proceed in the original direction, while the approaching one will, in its turn, pause or stop, until another one approaches to within a certain distance therefrom, when it will move on in the original direction. 55 Whether the blades are caused to pause, stop, or recede, will depend upon the length of the crank arms 21 and 22, and the ratio of the gears 13 and 17. It will be understood that these relations may be varied as 60 conditions require.

What is claimed is:

1. A mechanical movement including rotatable elements, and means for causing the stopping of one of the elements while another element approaches to within a pre-

determined distance therefrom and then continuing in the same direction the movement of the stopped element at a gradually increasing speed, and continuing the movement of the said other element at a reduced speed. 70

2. A mechanical movement including rotatable elements, and means for causing a retardation of one of the elements while another element approaches it and then continuing in the same direction the movement of the retarded element at a gradually increasing speed and the movement of the other element at a gradually reducing speed. 75

3. A mechanical movement including rotatable elements, and means for causing a retardation, of one of the elements at a reduced speed and the movement of another element toward the first element at a gradually increasing speed, and then continuing the movement of the first element in the original direction at a gradually increasing speed, and continuing the movement of the second element at a gradually reducing speed. 80

4. A mechanical movement including rotatable elements, means for driving the elements, and means operated by the driving means for causing the stopping of one of the elements while another element approaches, at a gradually increasing speed, to within a predetermined distance therefrom and then continuing the movement in the same direction, of the stopped element, at a gradually increasing speed, and the movement of the other element at a gradually reducing speed. 90

5. A mechanical movement including rotatable elements, means for driving the elements, and means operated by the driving means for causing a retardation of one of the elements while another element approaches it at a gradually increasing speed and then continuing the movement, in the original direction, of the retarded element 105 at a gradually increasing speed and the movement of the other element at a gradually reducing speed. 110

6. A mechanical movement including rotatable elements, means for driving the elements, and means operated by the driving means for causing a retardation and stopping movement of one of the elements at a reduced speed while another element approaches it at a gradually increasing speed, 115 and then continuing the movement of the first element in the original direction at a gradually increasing speed, and the second element at a gradually reducing speed. 120

7. A mechanical movement including a 125 constantly driven shaft, independently rotatable shafts, work elements on the independently rotatable shafts, and means operable by the constantly driven shaft for driving the independently rotatable shafts 130

to cause one of the shafts to stop while the other continues to rotate at a gradually increasing speed, and then to cause the stopped shaft to continue its rotation in the original direction at a gradually increasing speed, and the other shaft to continue at a gradually reducing speed.

8. A mechanical movement including a constantly driven shaft, independently rotatable shafts telescoped together and onto the driven shaft, and means operable by the constantly driven shaft for driving the rotatable shafts and for causing a retardation of one of the shafts, while the other shaft continues to rotate at a gradually increasing speed, and then continuing the movement of the retarded shaft at a gradually increasing speed, and the other shaft at a gradually reducing speed.

9. A mechanical movement including a constantly driven shaft, hollow shafts thereon, work elements on the hollow shafts, a stationary gear, an element rotatable with the

driven shaft, gears on the rotatable element engaged with the stationary gear, a second rotatable element connected with the first rotatable element and movable therewith, and means operable by the element carried gears for retarding and stopping each of the hollow shafts successively and continuing the movement thereof at a gradually increasing speed in the original direction.

10. A mechanical movement including a constantly driven shaft, hollow shafts mounted thereon and carrying work elements, a rock element fixed on each of the hollow shafts, a stationary gear, a rotatable element fixed on the driven shaft, gears on the rotatable element meshing with the stationary gear, crank shafts carried by the rotatable element, and links connected with the crank shafts and with the rock elements.

In testimony whereof, I affix my signature.

CHARLES L. JOHANNESSOHN.
